TRAY FOR SUGAR CUBES AND CREAMER

Marguerite H. Endter, 2096 Charnelton St.,
Eugene, Oreg. 97405

Filed Jan. 17, 1973, Ser. No. 324,500

Term of patent 7 years

Int. Cl. D7—99

U.S. Cl. D7—58

Fig. 1

Fig. 2

FIG. 1 is a side elevational view of the tray for sugar cubes and creamer,

FIG. 2 is a plan view thereof,

FIG. 3 is a sectional elevation taken along line 3—3 of FIG. 1,

FIG. 4 is a side elevational view on a reduced scale taken from the right hand side of FIG. 1, and

FIG. 5 is a bottom plan view of FIG. 4.

I claim:

The ornamental design for a tray for sugar cubes and creamer, substantially as shown.
